UNITED STATES PATENT OFFICE.

ROBERT W. JOY, OF BROOKLYN, NEW YORK, ASSIGNOR TO AMERICAN CAR AND FOUNDRY COMPANY, OF NEW YORK, N. Y., A CORPORATION OF NEW JERSEY.

DOOR-LOCKING DEVICE.

Application filed September 17, 1923. Serial No. 663,022.

To all whom it may concern:

Be it known that I, ROBERT W. Joy, residing at Brooklyn, county of Kings, State of New York, and being a citizen of the United States, have invented certain new and useful Improvements in Door-Locking Devices, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

20 In said drawings:

Figure 1 is a fragmentary side elevation of a hopper bottom dumping car equipped with a door locking means constructed in accordance with this invention, the door being shown locked in the fully closed position;

Figure 2 is a section taken on the line 2-2 of Figure 1;

Figure 3 is a fragmentary side elevation on a larger scale of the car shown in Figure 1 showing in full lines the door held in a partly closed position; and

Figure 4 is a central horizontal section through the latch housing, the latch being shown in plan view.

It is an object of this invention to provide an improved door latching means particularly for use with the dumping doors of cars. It is also an object of this invention to provide an improved door latching means adapted to retain the doors in a partly closed position as well as in a fully closed position.

In the drawings the invention is shown applied to a dumping car having side sills 1, side sheets 2, side posts 3, and hoppers comprising hopper side sheets 4 secured to the side sills 1 and side sheets 2 by rivets 5 which unite the side sheets 2 and side sills 1. The hopper side sheets 4 are reinforced along the door openings by Z-bars 7 secured to the hopper side sheets by rivets 8. The door openings in the hoppers are closed by doors 9 secured to the car body by hinges 10, the hopper doors being rein-

forced by Z-bars 11 having webs 12 and flanges 13 and 14, the Z-bars being secured to the doors 9 by rivets 15 which pass through flanges 14. At their ends the Z-bars 11 project beyond the doors 9 and the flanges 14 and part of the webs 12 are cut away. To the doors 9 rivets 16 secure brackets 17 to which pawls 18 are pivotally secured by pins 19.

To the hopper sheets 4, rivets 20 secure latch housings 21 having substantially U-shaped walls 22 formed integral with a connecting side wall 23. Each housing 21 is also provided with a reinforcing or partition wall 24, both the partition wall 24 and the side wall 23 being provided with bosses having openings in which is mounted a pin 25. The pin 25 is secured in position by the flange 26 on the boss 27 on the side wall 23 when the latch housing 21 is secured to the hopper side sheet 4. Mounted on the pin 25 is a latch 28 comprising a shank portion 29 and an irregularly shaped head portion 30, the junction of the head portion 30 and the shank 29 forming a shoulder 31 on the lower side of the shank 29 and a curved portion 32 on the upper side of the shank. The head 30 has a curved portion 33 and an angular portion which forms a shoulder 34 on the upper portion of the head. The shank 29 is provided on its upper surface with a lug 36 and upon its lower surface with a lug 35, the lug 35 being positioned on the shank so as to engage with the inner surface of the U-shaped wall 22 of the latch housing 21 and hold the latch 28 so that the latch will be raised by the engagement of the curved portion 33 by the web 12 of the Z-bar 11 as the door 9 is swung towards closed position.

When the door is locked in closed position, as shown in Fig. 1, the shoulder 31 on the latch 28 is in engagement with that portion of the flange 13 which projects beyond the side of the door 9, the shank 29 rests upon the web 12 of the Z-bar 11 and the pawl 18 is in engagement with the curved portion 32 of the shank 29, the pawl 18 assuming this position through gravity and serving to lock the latch 28 in engagement with the Z-bar 11 and hold the door 9 in the fully closed position. To release the door 9 the pawl 18 will be rotated in a clockwise direction, as shown in Fig. 1, engaging with the lug 36 on the latch 28 and permitting

- the latch 28 to be raised from engagement with the Z-bar 11 to release the door 9. To close the door, the door will be swung inwardly engaging the curved surface 33 of the latch 28 with the web 12 of the Z-bar 11. As the latch 28 engages with Z-bar 11, the pawl 18 will engage with the outer end of the latch and as the door is moved inwardly, the curved surface 33 of the latch 28 traveling over the web 12 of the Z-bar 11, the pawl 18 will be moved along the latch 28 until it drops in back of the shoulder 34 while the curved surface 33 still rests upon the web 12, as shown in Fig. 3. The engagement of the pawl 18 with the shoulder 34 of the latch 28 will retain the door in a partly closed position and enable the operator to apply a means for forcing the door to the fully closed position. The door will then be forced inwardly from the position shown in Fig. 3 to the position shown in Fig. 1, the curved surface 33 traveling on the web 12 of the Z-bar 11 until the shoulder 31 of the latch 28 drops in back of the Z-bar and in engagement with the flange 13 of the Z-bar at which time the pawl 18 will have traveled along the upper surface of the latch 28 and will have dropped into engagement with the curved portion 32 of the latch, as shown in Fig. 1, thus locking the latch 28 in engagement with the Z-bar 11 and locking the door in the fully closed position.
- What is claimed is:
1. The combination of a door, a latch for said door, and a locking pawl for said latch adapted to engage said latch to hold said door in partly closed position.
2. The combination of a door, a latch for said door adapted to hold said door in fully closed position, and a pawl adapted to lock said latch in engagement with said door, said pawl being adapted to engage said latch to hold said door in partly closed position.
3. The combination of a door, a latch for said door, and a locking pawl for said latch carried by said door, said pawl being adapted to engage said latch upon the closing of the door to hold said door in partly closed position.
4. The combination of a door, a pawl carried by said door, and a latch for said
- door having a shoulder engaged by said pawl to hold said door in partly closed position. 55
5. The combination of a door, a pivotally mounted latch having a shoulder adapted to engage said door to hold said door in fully closed position, and a locking pawl 60 for said latch, said latch having an oppositely disposed shoulder engaged by said pawl to hold said door in a partly closed position. 65
6. The combination of a dumping door, a latch for said door having means adapted to engage said door to hold said door in fully closed position and a pawl carried by said door and operative to lock said latch when said door is fully closed, said pawl being adapted to engage said latch to hold said door in a partly closed position. 70
7. The combination of a door, a latch for said door having means adapted to engage said door to hold said door in fully closed 75 position, a pawl operative to lock said latch when said door is fully closed, and means on said latch engaged by said pawl to hold said door in a partly closed position, said pawl being adapted to move to locking position as 80 said door is moved to fully closed position. 85
8. The combination of a door, a latch for said door having means adapted to engage said door to hold said door in fully closed position, a locking pawl for said latch operative when said door is fully closed, and means on said latch engaged by said pawl to hold said door in a partly closed position, said pawl being adapted to travel along said latch to locking position as said door is 90 moved to fully closed position and said latch moved to door locking position. 95
9. The combination of a dumping door, a latch for said door having means adapted to engage said door to hold said door in fully closed position and a pawl carried by said door and operative to lock said latch when said door is fully closed, said pawl being adapted to engage said latch to hold said door in a partly closed position. 100

In witness whereof I have hereunto set my hand in the presence of two witnesses.

ROBERT W. JOY.
